 Tubular Rivet and Stud Company, Quincy,
 Mass., a corporation of Massachusetts

Application April 9, 1947, Serial No. 740,421

9 Claims. (Cl. 134—58)

1

This invention relates to quenching apparatus for quenching a heated metal article in the process of being hardened.

The invention has for an object to provide novel and improved quenching apparatus capable of performing the quenching operation in a superior and economical manner and in which provision is made for controlling the quenching operation to the end that successive articles may be quenched under uniform conditions whereby to assure uniform hardening of successive articles.

A further object of the invention is to provide novel and improved apparatus of the character specified having novel provision for supporting an article to be quenched in a manner such as to effect self-alignment and firm engagement of the supporting elements with the article whereby to enable the quenching operation to be confined to the portions of the article to be hardened.

With these general objects in view, and such others as may hereinafter appear, the invention consists in the quenching apparatus and in the various structures, arrangements and combinations of parts hereinafter described and particularly defined in the claims at the end of this specification.

In the drawings illustrating the preferred embodiment of the invention, Fig. 1 is a view partly in side elevation and partly in cross section of quenching apparatus embodying the present invention; Fig. 2 is a front elevation of the apparatus shown in Fig. 1; Fig. 3 is a cross sectional view illustrating the mechanism for supporting the article during the quenching operation; Fig. 4 is a plan view of one of the article engaging elements as viewed from the line 4—4 of Fig. 3; Fig. 5 is a plan view of a cooperating article supporting member as viewed from the line 5—5 of Fig. 3; and Fig. 6 is an electrical diagram of control mechanism to be hereinafter described.

In general, the present invention contemplates novel and improved apparatus for quenching a heated metal article such as a steel tool, die, or the like to harden silicated portions thereof, the illustrated embodiment of the invention being particularly adapted for performing the quenching operation on a heated die member comprising a metal block having an opening or die aperture therein to harden wall portions of the aperture and the end portions of the die adjacent the aperture, the completed die member being adapted for use as a hollow rivet forming die.

In practice, the article or work to be hardened, hereinafter called the die member, is first heated to the required temperature in a separate furnace

and then placed and firmly clamped between die supporting nozzles having openings therein communicating with the opening in the die. Thereafter the quenching medium, preferably water under a predetermined and controlled pressure, is caused to flow through the supporting nozzles and the die aperture to perform the quenching operation and to effect hardening of the selected portions of the die as above described.

10 The invention contemplates die quenching apparatus capable of automatically performing the quenching operation under uniform conditions as to time, thus assuring uniform hardening of successive dies. In the preferred embodiment of the invention, provision is made for relatively moving the die engaging nozzles into firm clamping engagement with the die members and the apparatus may and preferably will include control mechanism for automatically initiating the flow 15 of water through the die member after the latter has been firmly clamped and for discontinuing the flow of water therethrough after a predetermined and adjustably variable length of time whereupon the nozzle members may be moved to release the die from clamping engagement therewith. The nozzle members for supporting and clamping the die therebetween are shaped to confine the quenching medium to the areas to be hardened, and, in practice, the nozzle members 20 are disposed in parallel face to face alignment with the engaging surfaces of the die member in order to provide a tight metal to metal seal whereby to prevent leakage of the quenching medium to other areas of the die member. In order to assure such alignment and to overcome any slight irregularities of the engaging surfaces, the nozzle members may and preferably will be provided with resilient base members capable of yielding upon clamping engagement of the nozzle 25 with the die to enable the nozzle members to tilt slightly and conform themselves to the plane of the surfaces of the die member to be quenched.

30 Referring now to the drawings, the illustrated quenching apparatus is particularly adapted for performing the quenching operation on a heated die member 10 having a substantially central opening 12 extending therethrough, the die member being herein shown as cylindrical in form and having flat and substantially parallel end surfaces. In general, the die member 10 is arranged to be clamped between metallic nozzle members 14, 16 engageable with the flat end surfaces of the die member 10 and having openings extending therethrough and communicating with the opening 35 in the die member 10 to permit passage of the

2

quenching medium therethrough. In operation, the die member is supported on top of the lower nozzle member 14 which is preferably mounted to be vertically adjusted with respect to the upper nozzle member 16, and, the latter may and preferably will be mounted to be vertically reciprocated into and out of cooperating engagement with the upper surface of the die member supported on the relatively stationary lower nozzle member 14.

As herein illustrated, the lower nozzle member 14 is mounted in a holder 18 having a reduced diameter portion 19 fitted into and detachably secured to the upper end of a vertical shaft 20 mounted for vertical adjustment in suitable bearings in a bracket 22 secured to the machine frame. The adjusting mechanism may comprise a rack 24 secured to the vertical shaft 20 and arranged to cooperate with a gear 26 fast on a horizontal shaft 28. The shaft 28 is also provided with a worm wheel 30 arranged to cooperate with a worm gear 32 fast on a shaft 34 which latter extends outside the bracket 22 and is provided with a hand wheel 36 by which the mechanism is operated to effect elevation or descent of the shaft 20 and the nozzle member 14 carried thereby for the purpose of adjustment to accommodate die members of different heights. The holder 18 may be detachably secured to the upper end of the vertical shaft 20 by set screws 38 and the shaft is prevented from rotating in the bracket 22 by the provision of a pin 40 carried by and extending from the lower end of the shaft 20 and engageable with a vertical slotted portion 42 in the bearing bracket, as illustrated.

The nozzle member 14 is fitted into a bore 35 formed in the upper end of the holder 18 and is provided with a resilient base member 44 in the form of an annular collar seated in the bottom of the bored opening. The resilient base member 44 may and preferably will comprise a synthetic rubber having high heat resisting and long wearing characteristics, although other resilient materials having similar characteristics may be employed for this purpose. The nozzle member 14 is held in the holder 18 by a retaining member 46 in the form of a cylindrical cap in threaded engagement with the upper end of the holder 18 and provided with a tapered opening arranged to fit over a correspondingly tapered peripheral portion of the nozzle member, as shown. In order to provide lateral support for the die member and to align it with the nozzle members 14, 16, a centering guide 48 may be provided which is arranged to fit snugly about the retaining member 46 and is provided with an internal shouldered portion arranged to rest on the upper edge of the retaining member. The centering guide 48 may and preferably will be provided with a plurality of radial slots 50 through which surplus water may escape into a drain pan 52 upon completion of the quenching operation and removal of the die member. As herein shown, the drain pan 52 is secured to the holder 18 and may be connected by a flexible tube 54 to a drain pipe 56.

The upper nozzle member 16 is carried by a similar but inverted holder 60 and is also provided with a resilient base member 62 which may be of the composition of the member 44, the nozzle member being held in the holder 60 by a threaded retaining member 64 having a tapered opening engageable with the conical or tapered outer surface of the nozzle member 16. The holder 60 is provided with a reduced diameter portion 68 detachably secured by set screws 70 to a hollow shaft 72 arranged to be vertically re-

ciprocated in a bearing member 14 through connections from a pneumatic cylinder 76 including a plunger shaft 78 connected to and forming an extension of the piston 80 of the pneumatic cylinder. The illustrated connection between the plunger shaft 78 and the hollow shaft 72 is designed to permit continued descent of the plunger shaft for a short distance after the nozzle member 16 has engaged the upper surface of the die member 10, and, as herein shown, the plunger shaft 78 is provided with a pin 82 passing through and extending from both sides thereof, the extended portions of the pin being engageable in a slot 84 formed in opposed sides of the hollow shaft 72 for limiting the movement of the plunger relative to the hollow shaft. As herein shown, the plunger shaft 78 is further provided with a compression spring 85 coiled thereabout and supported between a collar 86 on the plunger shaft and a shouldered portion 88 formed in the hollow shaft 72.

With this construction it will be observed that the spring 85 is arranged to urge the hollow shaft 72 to an outwardly extended position relative to the plunger shaft 78, being limited in its extended movement by the engagement of the pin 82 with the upper ends of the slot 84, and that upon operation of the air cylinder 76 to effect downward movement of the reciprocal unit, the upper nozzle member 16 is yieldingly engaged with the upper surface of the die member 10. It will be further observed that the plunger shaft 78 is capable of continued downward movement to compress the spring 85 and to effect tight clamping of the die member 10 between the nozzle members 14, 16.

In order to assure parallel alignment and substantially equalized pressure upon the engaging surfaces, the resilient base members or collars 44, 62 of the nozzle members 14, 16 respectively are adapted to yield slightly upon initial engagement of the reciprocating clamping unit with the die member 10 whereby to permit the nozzle members to conform themselves to the plane of the end surfaces of the die member thus affording a tight metal to metal seal and preventing leakage of the quenching fluid between the nozzles and the die during the quenching operation.

As herein illustrated, the pneumatic cylinder 76 is arranged to be controlled by a solenoid operated multiple valve unit of known construction, indicated generally at 90. The latter is arranged to communicate with the lower end of the cylinder by a pipe line 92 to effect the pneumatic movement of the piston in one direction, and, through a second pipe line 94 communicating with the upper end of the cylinder, is arranged to effect similar movement of the piston in the opposite direction. The valve unit 90 may be connected to any usual or preferred source of compressed air from a main pipe 95 through a pipe line 96 which may be provided with conventional apparatus for controlling the air including an air filter 98, oiler 100, pressure regulator 102 and pressure indicating gauge 104, as illustrated in Fig. 1.

In accordance with one feature of the present invention provision is made for automatically controlling the multiple valve unit to effect elevation of the reciprocal nozzle member 16 out of clamping engagement with the work after a predetermined length of time sufficient to assure adequate quenching of the die member for the hardening operation. Such automatic control mechanism is herein illustrated as comprising an elec-

trical circuit including a solenoid 106 for operating the valve unit 90 and which is arranged to be closed by a push button switch 108 for initiating operation of the air cylinder 76; a micro-switch 110 arranged to be closed upon initial descent of the plunger shaft 78 to maintain the circuit; and an adjustable time delay relay, indicated generally at 112, adapted to be set to effect opening of the circuit after a predetermined time has elapsed, as will be hereinafter more fully described. The micro-switch 110 is normally closed and is arranged to be maintained in its open position when the reciprocatory unit is in its elevated position by a contact bar 111 extended from and movable with the plunger shaft 78 so that, in operation, upon initial downward movement of the plunger shaft, in response to closing the circuit at the momentary contact switch 108, the contact bar 111 will leave the micro-switch 110 to permit it to maintain the circuit closed through the solenoid 106 during the quenching operation.

From the description thus far it will be observed that through the operation of the multiple valve unit 90, the piston 80 of the air cylinder 76 is actuated to effect descent of the upper nozzle member 16 into clamping engagement with the upper surface of the die 10 supported upon the lower cooperating nozzle member 14, and that after a predetermined time has elapsed, as controlled by the time delay relay 112, the air cylinder is actuated to effect elevation of the nozzle member 16 and the release of the die clamped thereby.

As herein shown, the quenching fluid is supplied to the apparatus from a main water line 120 through a pipe 122 to a solenoid operated water valve, indicated generally at 124, and having a flexible connection 126 to a pipe 128 extending from the lower holder 18. The pipe 128 communicates with a passageway 130 formed in the holder 18 in alignment with the opening in the lower nozzle member 14 and the opening in the resilient collar 44. The water then passes through the die member 10 to be quenched and through the upper nozzle member 16 and thence through a passageway 132 formed in the upper holder 60. The water line is continued through a pipe 134 connected to the holder 60 and through a flexible connection 136 to a drain pipe 138 connected to the main drain 56. The connecting pipe 122 may and preferably will be provided with pressure control means including an adjustable pressure regulator 140 and a pressure indicating gauge 142 whereby to enable the desired pressure to be adjusted and maintained.

The solenoid operated water valve 124 may be of a known type adapted to automatically start and stop the flow of water through the apparatus as controlled by the solenoid. As herein shown, the water valve may be provided with a drain pipe 60 144 for permitting the water to drain away from the lower nozzle member 14 through the pipe 128, flexible connection 126, and valve 124 when the water pressure is shut off.

As best shown in Fig. 3, the nozzle members 14, 65 16 are designed to confine the water to those portions of the die which it is desired to quench, each nozzle member being provided with an annular rim defining chamber 146, 147 respectively extending over the area adjacent the ends of the 70 opening. The upper nozzle member 16 is further provided with a plurality of relatively small apertures 148 whereby to restrict the passage of the water therethrough for most efficient results in the hardening operation. The portions of the 75

die thus hardened comprise the walls of the opening and the ends adjacent the opening, as indicated by the stipple work shown in Fig. 3.

Provision is also preferably made for automatically controlling the flow of water through the apparatus in a manner such as to initiate the flow of water after the die has been firmly clamped between the nozzle members, and, to discontinue the flow of water immediately prior to release of the die member from such clamping engagement. Such control mechanism is herein illustrated as comprising an electrical circuit including the solenoid 150 forming a part of the valve unit 124 and which is arranged to be energized by closing the circuit at a micro-switch 152. The normally open micro-switch 152 is arranged to be closed by the contact bar extension 111 upon descent of the plunger shaft 78 during its travel beyond the point at which the nozzle member 16 engages the die, that is, during the overthrow of the plunger shaft and yielding of the spring 85. Conversely, upon elevation of the plunger shaft 78, the extension 111 leaves the switch 152 upon initial upward movement thereof to effect opening of the circuit and closing of the valve to discontinue the flow of water before the nozzle 16 is removed from clamping engagement with the die. Thus, in operation, the water is controlled to prevent the flow thereof except at the time when the nozzles 14, 16 are in clamping engagement with the die 10.

Provision is also made in the preferred embodiment of the invention for directing a stream of air toward the upper nozzle member 16 for the purpose of blowing away any droplets of water remaining on the nozzle at the completion of the quenching operation and after the die member 10 has been removed. As herein shown, an air line 156 coiled in the drain pan 52 and terminating in an upturned nozzle portion 158 directed toward the nozzle, is connected to a manually operated push button valve, indicated at 160 and the valve 160 is connected by an air line 162 to the main air line 95. In the operation of the apparatus, the operator may press the button valve 160 to release a stream of air against the nozzle 16 immediately prior to placing a die in the apparatus to be quenched thus assuring that the nozzle is substantially dry when it engages the heated metal die 10 in clamping engagement.

From the description thus far it will be observed that in the operation of the apparatus, the operator first places the heated die in the centering guide 48 and then merely presses the start button 108, the apparatus being then capable of automatically following through a complete cycle of a quenching operation including clamping of the die in water tight engagement, initiating the flow of water therethrough, discontinuing the flow of water after a predetermined time has elapsed, and then releasing the die from clamping engagement, without further attention from the operator, whereby to assure uniformity as to time of quenching and degree of hardness of successive dies thus treated.

Referring now particularly to Fig. 6, the electrical circuits for automatically controlling the apparatus as above described includes an air valve circuit having a line 164 from the main switch 166 to the push button or momentary contact switch 108 and a line 168 leading from the switch to one end of the solenoid coil 106 of the valve unit 90. The other end of the coil 106 is connected by a lead 170 to the main line

172. The closing of the contacts at the momentary contact switch 108 energizes the solenoid 106 to effect operation of the multiple valve unit 90 to start the piston 80 and the plunger shaft 78 on their downward stroke and upon initial downward movement of the latter, the contact extension 111 leaves the micro-switch 110 to permit it to close and continue the circuit through the coil 106 through the time delay relay 112.

As herein shown, the circuit through the coil 106, micro-switch 110 and time delay relay 112 includes a lead 174 from the main line 164 to one terminal of the micro-switch 110, a lead 176 from the other terminal of the switch to the time delay relay, and a lead 178 from the time delay relay to one end of the coil 106, the circuit being completed through the coil and through lead 170 to the main line 172.

The water valve circuit includes the micro-switch 152 and solenoid coil 150 of the water valve unit 124 which are herein shown as connected by a lead 180 from the main line 172 to one terminal of the switch 152, a lead 182 from the other terminal to one end of the coil 150. The water valve circuit is continued through the coil and through a lead 184 to the main line 164. Thus, in the operation of the apparatus, closing of the contacts of the micro-switch 152 by the extension 111 at the end of the descending stroke of the plunger shaft 78, after the die member 10 has been firmly clamped, energizes the solenoid coil 150 to operate the valve and start the flow of the water through the apparatus to quench the die. After a predetermined length of time has elapsed, as controlled by the adjustable time delay relay 112, the air valve circuit is opened to effect elevation of the plunger shaft 78, and, during the initial portion of the elevating movement, before the die is released, the water valve circuit is opened at the micro-switch 152 to effect closing of the water valve and discontinuance of the flow of the water through the die. Thereafter, as the plunger shaft 78 approaches the end of its elevating stroke, the contact extension 111 engages the normally closed micro-switch 110 to effect opening of the air valve circuit to close the air valve and to reset the time delay relay for a subsequent cycle of operation.

From the above description it will be observed that the present quenching apparatus is provided with control mechanism by which the quenching operation may be automatically performed to assure uniform hardening of successive parts placed therein independently of operator control. It will be further observed that the present apparatus is capable of clamping the part to be quenched in a manner such as to effect self alignment of the clamping members with the engaging surfaces of the part or work whereby to provide firm and water tight engagement with the work thus confining the quenching operation to the portions of the work desired to be hardened.

While the preferred embodiment of the invention has been herein illustrated and described, it will be understood that the invention may be embodied in other forms within the scope of the following claims.

Having thus described the invention, what is claimed is:

1. Die quenching apparatus comprising a pair of die engaging nozzles mounted to be relatively moved into clamping engagement with opposed surfaces of a die having an aperture therethrough

75 and in communication with the die aperture, means for effecting a flow of the quenching medium through the nozzles and the die, said nozzles being formed to confine the quenching medium within the outer edges of said opposed die surfaces, and automatically operated and selectively adjustable control means for controlling the flow of the quenching medium having provision for automatically initiating the flow immediately upon water-tight clamping engagement of the nozzles with the die and for thereafter automatically discontinuing the flow after a predetermined time has elapsed and immediately prior to disengagement of the nozzles with the die whereby to prevent application of the quenching medium to other than the selected portions of the die.

2. In die quenching apparatus comprising a pair of die engaging nozzles mounted to be relatively moved into and out of substantially water-tight engagement with opposed surfaces of a die having an aperture therethrough and in communication with the die aperture, said nozzles being formed to confine the quenching medium within the outer edges of said opposed die surfaces, a water line connected to said nozzles, a valve in said water line, and automatically operated and selectively adjustable control means actuated by the movement of the nozzles into and out of engagement with the die for operating said valve to automatically initiate the flow of water through the nozzles and the die immediately after the nozzles are in water-tight engagement with the die and to thereafter automatically discontinue the flow after a predetermined time has elapsed and immediately prior to disengagement of the nozzles with the die whereby to prevent application of the quenching medium to other than the selected portions of the die.

3. Die quenching apparatus comprising a pair of die engaging nozzles, means for reciprocating the nozzles into and out of substantially water-tight engagement with opposed surfaces of a die having an aperture extending therethrough and in communication with the die aperture, said nozzles being formed to confine the quenching medium within the outer edges of said opposed die surfaces, means for effecting a flow of water through the die aperture to perform the quenching operation, and automatically operated and selectively adjustable control means for controlling said reciprocating means to cause the nozzles to remain in operative engagement with the die for a predetermined length of time independently of the operator, and for thereafter enabling the reciprocating means to automatically move the nozzles out of operative engagement with the die, and means actuated by the reciprocal movement of the nozzles into and out of quenching engagement with the die for initiating the flow of water through the die immediately upon firm engagement of the nozzle with the die, and for discontinuing the flow of water through the die immediately prior to disengagement of the nozzles from the die whereby to prevent application of the water to other than the selected areas of the die.

4. Die quenching apparatus comprising a pair of die engaging nozzles, means for reciprocating the nozzles into and out of substantially water-tight engagement with opposed surfaces of a die having an aperture extending therethrough and in communication with the die aperture, said nozzles being formed to confine the quenching medium within the outer edges of said opposed die

surfaces, means for effecting a flow of water through the die aperture to perform the quenching operation, and automatically operated and selectively adjustable control means for controlling said reciprocating means to cause the nozzles to remain in operative engagement with the die for a predetermined length of time independently of the operator, and for thereafter enabling the reciprocating means to automatically move the nozzles out of operative engagement with the die, means actuated by the reciprocal movement of the nozzles into and out of quenching engagement with the die for initiating the flow of water through the die immediately upon firm and water-tight engagement of the nozzles with the die and for discontinuing the flow immediately prior to disengagement of the nozzles from the die whereby to prevent application of the water to other than the selected areas of the die, and independently operated means for directing a stream of air against the exterior of at least one of said nozzles after disengagement whereby to remove excess water from the exterior surfaces thereof prior to a subsequent quenching operation.

5. Die quenching apparatus comprising a pair of die engaging nozzles, pneumatically operated means for reciprocating the nozzles into and out of substantially water-tight engagement with opposed surfaces of a die having an aperture extending therethrough and in communication with the die aperture, said nozzles being formed to confine the quenching medium within the outer edges of said opposed die surfaces, means for effecting a flow of water therethrough to perform the quenching operation, air valve means associated with said pneumatically operated means, and automatically operated and selectively variable time control means for operating said air valve means adapted to maintain the nozzles in quenching engagement with the die for a predetermined length of time and for thereafter automatically effecting disengagement of the nozzles from the die, water valve means associated with said quenching means, and means controlled by said reciprocating means for operating said water valve to initiate the flow of water immediately upon firm engagement of the nozzles with the die and for discontinuing the flow of water immediately prior to disengagement of the nozzles from the die whereby to prevent application of the water to other than the selected areas of the die.

6. Die quenching apparatus comprising a pair of die engaging nozzles, means for reciprocating the nozzles into and out of substantially water-tight engagement with opposed surfaces of a die having an aperture extending therethrough and in communication with the die aperture, said nozzles being formed to confine the quenching medium within the outer edges of said opposed die surfaces, means for effecting a flow of water therethrough to perform the quenching operation, automatically operated and selectively adjustable control means including a time delay relay for controlling said reciprocating means to cause the nozzles to remain in operative engagement with the die for a predetermined length of time, and for thereafter enabling the reciprocating means to automatically move the nozzles out of operative engagement independently of the operator, water valve means associated with said quenching means, and means controlled by said reciprocating means for operating said water valve to initiate the flow immediately upon firm engagement of the nozzles with the die and for

discontinuing the flow immediately prior to disengagement of the nozzles and the die whereby to prevent application of the water to other than the selected areas of the die.

5 7. Die quenching apparatus comprising a pair of die engaging nozzles, means for reciprocating the nozzles into and out of substantially water-tight engagement with opposed surfaces of a die having an aperture extending therethrough and in communication with the die aperture, said nozzles being formed to confine the quenching medium within the outer edges of said opposed die surfaces, means for effecting a flow of water therethrough to perform the quenching operation, automatically operated and selectively adjustable control means including a time delay relay for controlling said reciprocating means to cause the nozzles to remain in operative engagement with the die for a predetermined length of time, and for thereafter enabling the reciprocating means to automatically move the nozzles out of operative engagement independently of the operator, water valve means associated with said quenching means, and means controlled by said reciprocating means for operating said water valve to initiate the flow immediately upon firm engagement of the nozzles with the die and for discontinuing the flow immediately prior to disengagement of the nozzles and the die whereby to prevent application of the water to other than the selected areas of the die, said reciprocating means having provision for effecting yielding engagement of the nozzles with the die and having a portion capable of independent movement after engagement and before disengagement of the nozzles with the die for effecting operation of said water valve means.

8. Die quenching apparatus comprising a pair of die engaging nozzles, pneumatically operated means for reciprocating the nozzles into and out of substantially water-tight engagement with opposed surfaces of a die having an aperture extending therethrough and in communication with the die aperture, means for effecting a flow of water therethrough to perform the quenching operation, solenoid operated air valve means associated with said pneumatically operated means, control means including an adjustable time delay relay for controlling said solenoid operated air valve to cause the nozzles to remain in operative position with the die for a predetermined length of time and for thereafter enabling the reciprocating means to move the nozzles out of operative engagement, solenoid operated water valve means associated with said quenching means, and means actuated by said reciprocating means for controlling said solenoid operated water valve to initiate the flow after firm engagement of the nozzles with the die and for discontinuing the flow immediately prior to disengagement of the nozzles from the die.

9. Die quenching apparatus comprising a pair of die engaging nozzles, pneumatically operated means for reciprocating the nozzles into and out of substantially water-tight engagement with opposed surfaces of a die having an aperture extending therethrough and in communication with the die aperture, means for effecting a flow of water therethrough to perform the quenching operation, air valve means associated with said pneumatic means to effect reciprocation of the nozzles, and electrical control means comprising a circuit including a solenoid operatively connected to said air valve means, a momentary contact switch for closing the circuit to said air

valve solenoid to effect movement of the nozzles into die engaging position, an adjustable time delay relay adapted to continue the circuit to the air valve solenoid after the momentary contact switch is opened and for opening the circuit to the air valve solenoid after a predetermined length of time to effect disengagement of the nozzles with the die, water valve means associated with said quenching means, a second circuit including a solenoid operatively connected to said 10 water valve means, and a switch in said second circuit actuated by said reciprocating means for operating said water valve to initiate the flow of water after firm engagement of the nozzles, and for discontinuing the flow immediately prior to 15 disengagement of the nozzles from the die.
